UNITED STATES PATENT OFFICE.

CHARLES L. BRALEY, OF CHICAGO, ILLINOIS, ASSIGNOR OF ONE-HALF TO CHARLES F. NOFTZGER, OF CHICAGO, ILLINOIS, AND ONE-HALF TO THE AMERICAN LAUNDRY MACHINERY COMPANY, OF CINCINNATI, OHIO, A CORPORATION OF OHIO.

STARCH EXTRACTOR.

Application filed August 11, 1921, Serial No. 491,528. Renewed January 21, 1926.

To all whom it may concern:

Be it known that I, CHARLES L. BRALEY, a citizen of the United States, residing at Chicago, county of Cook, State of Illinois, 5 have invented certain new and useful Improvements in Starch Extractors, of which the following is a specification.

This invention relates to improvements in laundry apparatus.

10 The main objects of this invention are:

First, to provide an improved laundry apparatus by means of which laundry may be rapidly starched and the surplus starch extracted with a relatively small amount of 15 labor and handling.

Second, to provide an improved laundry apparatus by means of which laundry may be rapidly starched and the surplus starch extracted with a minimum of wear.

20 Third, to provide an improved laundry apparatus which is effective in uniformly impregnating garments with starch and at the same time very economical in the amount of starch used.

25 Fourth, to provide an improved laundry apparatus which is effective in draining and extracting the water from the wash.

Further objects, and objects relating to 30 structural details, will definitely appear from the detailed description to follow.

I accomplish the objects of my invention by the devices and means described in the following specification. The invention is clearly defined and pointed out in the 35 claims.

A structure which is a preferred embodiment of my invention is clearly illustrated in the accompanying drawing, forming a part of this specification, in which:

40 Fig. I is a detail side view, partially in vertical section, of my improved laundry apparatus, the laundry basket being shown in raised position by dotted lines, the plunger being shown in retracted position by

45 full lines and its supporting yoke partially open by dotted lines.

Fig. II is a plan view.

Fig. III is an enlarged detail section on a line corresponding to line 3—3 of Fig. II, 50 the chute being shown in inoperative position by full lines and in extended or operative position by dotted lines.

Fig. IV is an enlarged detail plan view

showing details of the nut for the extractor plunger actuating screw.

Fig. V is a side elevation of my improved laundry apparatus shown in relation to a washing machine illustrating its adaptation for extracting water from laundry.

In the drawings, similar reference characters refer to similar parts throughout the several views, and the sectional views are taken looking in the direction of the little arrows at the ends of the section lines.

Referring to the drawing, I provide a receptacle 1 preferably of a general rectangular cross section. This is supported on legs 2 at a convenient height for the operator. The laundry basket 3 is made up of a framework 4 having wire walls 5 secured thereto. 70 This basket is pivoted at 6 so that it may be lowered into the receptacle as shown in full lines in Figs. I and II or raised therefrom as shown by dotted lines in Fig. I.

The receptacle 5 is adapted to contain 75 starch so that when the basket is lowered therein the clothes are submerged in the starch. When used for extracting water the basket serves as a drainer and as a charging means for the extractor.

The bracket 7 is provided with a pivoted rest 8 for supporting the basket in its raised position. When in this raised position the bottom 9 of the basket is inclined to facilitate the discharge of the clothes.

I mount an extractor cylinder 10 upon the pivot side of the receptacle. The upper edge of this cylinder is somewhat lower than the pivot 6. A chute 11 is mounted on the pivot 6 so as to be swung over to rest on the top of the basket as shown in full lines in the drawing or swung over to rest on the top of the cylinder as shown by dotted lines in Fig. III and bridging the space between the basket and cylinder, thereby facilitating the transfer of the clothes from the basket to the cylinder.

The extractor cylinder is provided with an inner or false bottom 12 having holes therein through which the starch may escape to the return pipe 13, which is connected to the bottom of the starch receptacle. The pipe 13 is provided with a check valve 14. The plunger 15 is provided with a face 16 of rubber. The actuating screw 17 for this plunger is carried by a yoke 18 pivoted at

19 to swing away from the starch receptacle, so that it is out of the way when the clothes are being transferred. A latch 20 holds the yoke in its closed position. The 5 nut for the screw is formed of sections 21 which are mounted in a seat 22 in the yoke so as to be moved into and out of engagement with the screw, thus permitting the rapid adjustment of the screw to the work or raising it from the work. These nut members 21 are shifted by means of the forked slide 23, which has slots 24 in its arms, so that as 10 this slide is moved back and forth the nut sections are shifted into and out of operative 15 position. A bridge-piece 25 holds the nut sections in their seat in the yoke.

When used for starching, the starch is placed in the receptacle, the articles to be starched are thrown into the basket which is lowered into the receptacle, so that the clothes are submerged in the starch. When the basket is filled or the desired number of articles have been placed therein the basket is raised to its elevated position and supported by means of the rest 8, the yoke 18 is thrown back and the chute 11 thrown over onto the extractor cylinder. The clothes are then pushed into the extractor cylinder, the chute swung back and the yoke closed, the 20 latch 20 automatically engaging. The plunger may then be dropped down to engagement with the clothes by releasing the split nut and the nut reengaged, when the screw is actuated through its hand wheel 26, the 25 surplus starch is forced out of the clothes and through the return pipe 13 to the starch receptacle. The actuating screw is then returned to its raised position and the yoke thrown back so that the clothes may be removed. The starch is extracted without injury to the garments or their buttons or the like. The pressure of the plunger on the garments forces the starch through the same so that while the surplus is extracted, it 30 insures that the starch reaches all parts of the garments.

My improved laundry apparatus is capable of very rapid and easy manipulation and a large quantity of articles may be starched with comparatively little labor and effort.

In Fig. V, I show my improved laundry apparatus in operative relation to a washing machine 27. The wash is lifted from the washing machine into the basket 3 from

which the water drains into the receptacle 55. 1. The receptacle 1 is provided with a drain cock 28 from which the water flows to the gutter, usually provided in laundries. When drained, the clothes are discharged into the extractor. Water is forced out as is described for the starch. The water may be discharged directly through the drain cock 29 or returned to the receptacle 1, if desired. When used for extracting water, the legs 2 are preferably provided with wheels 30, so 60 that the apparatus may be moved from machine to machine. The structure is compact and economical to produce.

I have illustrated and described my improvements in embodiments which I find 70 very satisfactory. I have not attempted to illustrate or describe certain modifications which I contemplate, as I believe the structure illustrated will enable those skilled in the art to which my invention relates to 75 embody or adapt the same as may be desired.

Having thus described my invention, what I claim as new and desire to secure by Letters Patent, is:

1. In an apparatus of the class described, 80 the combination of a receptacle, a foraminated basket mounted in said receptacle to be lowered therein or raised therefrom for discharging the contents, an extractor cylinder disposed at the side of said receptacle whereby the articles may be discharged from the basket to said cylinder, a foraminated inner bottom in said extractor cylinder, a return pipe connecting said cylinder below its said inner bottom to said receptacle, said return 90 pipe being provided with a check valve, a plunger for said cylinder adapted to force the extracted liquid from said cylinder to said receptacle, and means for actuating said plunger.

2. In an apparatus of the class described, 95 the combination of a starch receptacle, an extractor cylinder, a return pipe connecting said cylinder to said receptacle, said return pipe being provided with a check valve, a 100 plunger for said cylinder adapted to force the starch extracted from the extractor cylinder into said receptacle, and means for actuating said plunger.

In witness whereof, I have hereunto set 105 my hand and seal.

CHARLES L. BRALEY. [L. S.]
